US0D1095512S

(12) **United States Design Patent** (10) **Patent No.:** **US D1,095,512 S**
(45) **Date of Patent:** **** Sep. 30, 2025**

(54) **DATA PROCESSING EQUIPMENT HOUSING**

(71) Applicant: **SITA B.V.**, Rotterdam (NL)

(72) Inventors: **Jeroen van Rijnberk**, Rotterdam (NL);
Johannes Theodorus Georgius Roelofsen, Rotterdam (NL); **Mathieu Eduard Keizer**, Rotterdam (NL); **Swen van Klaarbergen**, Rotterdam (NL)

(73) Assignee: **SITA B.V.**, The Hague (NL)

(**) Term: **15 Years**

(21) Appl. No.: **29/868,752**

(22) Filed: **Dec. 13, 2022**

(30) **Foreign Application Priority Data**

Jun. 13, 2022 (EM) 009060056-0004

(51) **LOC (15) Cl.** **14-02**

(52) **U.S. Cl.**

USPC **D14/303**; D18/4.4; D18/53

(57) **CLAIM**

The ornamental design for a data processing equipment housing as shown and described.

DESCRIPTION

FIG. 1 is a front perspective view of a data processing equipment housing.

FIG. 2 is a back perspective view thereof.

FIG. 3 is a front view thereof.

FIG. 4 is a back view thereof.

FIG. 5 is a top view thereof.

FIG. 6 is a bottom view thereof.

FIG. 7 is a left view thereof; and,

FIG. 8 is a right view thereof.

The broken lines shown in the drawings illustrate portions of the electronic device that form no part of the claimed design.

1 Claim, 8 Drawing Sheets
